[57] **CLAIM**

The ornamental design for a mirror, as shown and described.

DESCRIPTION

FIG. 1 is a front view of an embodiment of the design.

FIG. 2 is a front, left side perspective view of the embodiment of the design, and the front, right side perspective view is a mirror image.

FIG. 3 is a right side view of the embodiment of the design, and the left side view is the mirror image; and,

FIG. 4 is a partial cross-section of the embodiment of the design at 4—4 in FIG. 1.

The rear, top and bottom views of the embodiment of the design are of a plain and non-ornamental back, top and bottom, respectively.

The broken lines are for environmental purposes only and form no part of the claimed design.
